[57] CLAIM

We claim the ornamental design for a set of index tab file cards, as shown and described.

DESCRIPTION

FIG. 1 is a front elevational view of one of a set of index tab file cards showing our new design, with the index tab on the left;

FIG. 2 is a front elevational view of the second of a set of index tab file cards;

FIG. 3 is a front elevational view of the set of index tab file cards; and,

FIG. 4 is a front perspective view of FIG. 3.

The undisclosed rear of each of the cards is plain and unornamented. The rail openings depicted by means of broken lines in FIGS. 1 through 4 have been shown for illustrative purposes only and form no part of the claimed design.
